STEAM HEATING SYSTEM

Grove Starr, Pennhurst, Pa.

Application February 1, 1930, Serial No. 425,233
Renewed August 11, 1934

18 Claims. (Cl. 236—40)

This invention relates to a steam heating system and its control.

It is primarily an object of the invention to provide a steam heating system which will furnish a substantially constant temperature to a room or rooms by means of regulated intermittent impulses of steam from a constant pressure source into a conventional system of radiators. These regulated intermittent impulses are governed by means of a mechanism whose operation depends upon the heating effect of the condensate from one or more pilot radiators or "condensing devices" to which is added the additional effect of steam bled from each impulse of the regulated steam supply which feeds the conventional radiators. The timing of the impulses of regulated steam to the conventional radiators may be determined by the length of time it takes the steam, bled from each impulse, to reach the regulating mechanism. This timing can be suitably adjusted by inserting between the regulating mechanism and the source of the impulses of regulated steam a second condensing device such as a radiator fed through an adjustable valve, or even a suitable pipe fed through a needle valve or orifice plate.

It is a further object of the invention to provide a system of this kind wherein an outstanding advantage is that each impulse of steam is supplied to the conventional system of radiators under considerable pressure so that these radiators are supplied with steam quite rapidly. In this way steam is supplied to the most remote radiators substantially as soon as it is supplied to the radiators near to the source of supply, thus tending to give a very uniform temperature to the space to be heated.

A still further object of the invention is to provide a system of this kind presenting the outstanding advantage that it permits steam to be condensed in the conventional radiators to a pressure lower than atmospheric, or even lower than the pressure in the return line. This materially increases the thermal efficiency of the steam heating system by giving a condensate at a relatively low temperature. The partial vacuum obtained in the conventional radiators between impulses of steam also aids the rapid introduction of steam in the next impulse.

A further object of the invention is to provide a system of this kind embodying a plurality of radiators, one of which constitutes a pilot radiator automatically controlling means for regulating the admission of steam to the remaining radiators.

Another object of the invention is to provide a system of this kind wherein the delivery of steam through the feed line is under control of a thermostatically operated valve, together with means whereby the operation of the thermostat is under control of the varying temperature of the condensate from a pilot radiator interposed in the system, the temperature of the condensate from the pilot radiator being variable in accordance with the variations in temperature of the outside air surrounding the pilot radiator.

An additional object of the invention is to provide a system of this kind wherein a control valve within the feed pipe for the system is operated by a thermostat under control of the temperature changes of the condensate from a pilot radiator, together with means for reheating the condensate to function the thermostat to close the valve before overshooting of the admission of steam within the system.

A still further object of the invention is to provide a system of this kind having interposed therein thermostatically operating means for constantly impulsing the steam into the system when required, the vacuums occurring between impulses facilitating the liberation of the heat.

The invention consists in the details of construction and in the combination and arrangement of the several parts of my improved system whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:—

Figure 1 is a view in elevation and of a diagrammatic character illustrating an apparatus or system constructed in accordance with an embodiment of my invention;

Figure 2 is a view partly in section and partly in elevation illustrating the thermal control valve herein employed;

Figure 3 is a diagrammatic view illustrating another embodiment of my apparatus or system;

Figure 4 is a diagrammatic view of a still further embodiment of the invention.

In the embodiment of my invention as particularly illustrated in Figure 1 is disclosed an apparatus or system particularly intended for use in connection with the steam heating of a

building and while I illustrate but one of my controlling devices, it is to be understood that as many may be employed and so located as the requirements of practice may necessitate.

5 As disclosed in the accompanying drawings, 1 denotes a steam line leading from a suitable source of supply and which has interposed therein at a desired location a main supply valve 2 of any preferred construction. The line 1 also 10 has interposed therein and inwardly of the valve 2 a conventional steam strainer 3. A distribution line 4 is mounted and located as desired and is adapted for communication in a well known way with the conventional radiators, such radiators 15 to be positioned of course in accordance with the necessities of practice to assure the proper heating of the building.

As these regular radiators and their connections in themselves form no part of the present invention a detailed description and illustration thereof is not believed necessary as this will be readily understood by those persons familiar with steam heating practice.

It is also to be understood that a return line 25 5 is employed and with which the line 1 in advance of the valve 2 communicates through the medium of the line 6 in which is interposed a condensate trap 7. This is also well known in steam heating equipment.

30 The line 1 beyond the strainer 3 has in communication therewith a line 8 leading to a hot water generator or heater as is the general custom, thus using part of the steam to heat water for general purposes in and about the 35 building. This, however, is no part of the invention but shows that steam for any other purpose must be secured from the pressure side. A connection from line 8 through valve 11 forms a bypass to the heating system. In advance of 40 the first communication between the lines 1 and 8 and interposed in the line 1 and coacting in a well known manner with the line 8, is a reducing valve 9, said valve being provided to assure constant pressure into a pilot radiator 16.

45 It is also to be understood that the line 8 has a second communication, as at 10, with the line 1 and which communication is normally closed by a conventional bypass valve 11.

Interposed in the line 1 between its two points 50 of communication with the bypass line 8 are the spaced valves 12 and 14, and interposed between these valves 12 and 14 is a thermally operated balanced valve 15. This valve 15 may be of any preferred construction and as I am not the inventor of such valve it is believed that a detailed description and illustration thereof is unnecessary as a valve of this type is also well known to those engaged in steam heating work.

In addition to the regular radiators my improved system has interposed therein a pilot radiator 16 and a compensating radiator 17. The pilot radiator 16 has in communication therewith a pipe line 18 leading from the line 1 at a point between the reducing valve 9 and the 65 valve 12, thus assuring delivery of steam under constant pressure into the pilot radiator 16. The line 18 has interposed therein a limiting valve 19 or its equivalent of any desired construction whereby the flow of steam through the line 18 from the line 1 can be fixed and maintained as required.

Leading from the pilot radiator 16 is a return pipe line 20 continued by a pipe line 21. This pipe line 21 is in communication with an end 70 portion of a casing or shell 22 which provides

a pocket for a thermostatic element 23. The casing or shell 22 also has associated therewith a thermometer 24. The thermostatic element 23 is in operative connection, as at 25, with the valve 15 so that upon expansion of the thermostat 23 the valve 15 will be correspondingly closed and vice versa.

5 In this embodiment of my invention the thermostatic element 23 constitutes a bulb containing a suitable volatile liquid which is also contained within a suitably directed tubular member. This member is in communication with a bellows 26 which, upon expansion or contraction of the liquid, results in the desired operations of the valve 15.

10 While this valve 15 is illustrated in detail in Figure 2 of the drawings, I wish to again state that I am not the inventor of this particular valve and, therefore, do not make any claim as to its specific or particular construction. It is also to 20 be understood that it is possible to employ other mechanisms for operating the valve 15 in lieu of this particular arrangement and, therefore, I do not wish to be understood as limiting myself to any special form of valve.

15 The distributing line 4 has leading therefrom a pipe line 27 which is in communication with the compensating radiator 17 and interposed in this line 27 is a valve 28 of any desired type which limits the flow of steam into the compensating 30 radiator 17 for a purpose to be hereinafter particularly mentioned. The radiator 17 also has a return line 20' leading therefrom to the pipe 21.

25 Leading from the casing or shell 22 is a pipe line 29 in communication with a condensate trap 31 which discharges through the return riser 31 in communication with the main return pipe 5. The trap 30 operates to relieve the condensate occurring within the line 29 without reducing 40 the pressure therein.

30 The line 27 has leading therefrom a pipe line 32 in communication with a condensate trap 33 also discharging in the return riser 31, said trap 33 serving to relieve condensation occurring within the pipe line 32 or within the portion of the pipe line 27 between the valve 28 and the communication between said pipe line 27 and radiator 17.

35 It is to be noted that the pipe line 29 extends into the casing or shell 22 and terminates a desired distance above its bottom to retain within the casing or shell 22 a certain amount of water of condensation, and the amount so held within the casing or shell 22 may be varied or regulated 55 by raising or lowering the receiving end of the pipe line 29 within said casing or shell 22.

40 Leading from the pipe line 18 is a pipe line 34 which delivers to a condensate trap 35, said trap 35 discharging in the return riser 31. This trap 35 60 operates to relieve condensation occurring in the line 18 beyond the limiting valve 19, yet maintaining the pressure within such portion of the line 18.

45 The bypass valve 11 is normally closed and the valves 12 and 14 normally open. When the main supply valve 2 is opened the steam will pass through the pipe line 1 and the distributor pipe line 4 to properly fill the regular radiators and at the same time steam will pass through the pipe line 18 and beyond the properly set valve 70 19 to the pilot radiator 16, at the same time the steam will be passing through the pipe line 27 to the compensating radiator 17.

50 With the temperature surrounding the pilot 75

radiator 16 above the desired predetermined temperature of the building, the condensate occurring within said pilot radiator will be delivered through the lines 20 and 21 into the casing or shell 22 and said condensate within the casing or shell being of a temperature higher than that at which the thermostat 23 operates to open the valve 15, and will hold such valve 15 closed until the temperature of the air surrounding the pilot radiator 16 drops to such an extent that the pilot radiator 16 will deliver condensate to the casing or shell 22 of a temperature below the point that the thermostat functions to open the valve 15. Upon opening of the valve 15 steam will be delivered to the regular radiators of the system and through the pipe line 27 to the compensating radiator 17 and through said radiator 17 and the pipe lines 20' and 21 to the casing or shell 22, thus effecting a reheating of the condensate within the casing or shell 22 from the pilot radiator 16 and, of course, at the same time reheats the thermostat 23. This results in the required functioning of the thermostat to again close the valve 15. By predetermined setting of the valve 28 proper timing will be obtained for the closing of the valve 15 to assure the proper compensation of the thermostat 23.

The casing or shell 22 has associated therewith a thermometer 24 which is used to facilitate the setting of the valve 19. To make an efficient pilot radiator 16 that will satisfactorily deliver condensate of varying temperatures as effected by the temperature of the air coming in contact with the radiator 16, the supply of steam must be fixed and maintained so that the pilot radiator 16 will deliver condensate at the temperature at which the thermostat functions to close the valve 15 when the temperature of the air coming into contact with the pilot radiator 16 or any part thereof is at a predetermined degree. This temperature of the condensate within the casing or shell 22 can be readily determined by the readings of the thermometer 24. The readings of the thermometer 24 also facilitate the initial setting of the valve 15 and more especially its associated weight and spring.

When the outside temperature is abnormally low, it is oftentimes of advantage to provide means to raise the inside temperature above its regular degree. I find that this can be readily accomplished by placing a small radiating unit 36 in the outside atmosphere, said unit being arranged through the medium of the pipe line 37 in parallel with the pilot radiator 16.

My improved system as hereinbefore described also establishes a governed impulse method of flow for the steam or may be further defined as affording a regulated impulse method. It is believed to be apparent from the foregoing that the control of the flow of the steam is intermittent. This is of decided advantage as the vacuums created between impulses serve to materially facilitate the extraction of heat. This admission of the steam into the system in impulses is also of decided advantage in aiding the required circulation of steam through the system and this is equally true even under high vacuum as during the admission period the steam moves rapidly.

In view of the foregoing it is believed that the operation of the invention is clearly understood but it may be again set forth that the steam enters the heating and temperature regulating system by means of the pipe 1 shown in the lower right hand corner of Figure 1 of the drawings, and is brought to a definite constant pressure by the conventional

automatic pressure reducing valve 9. A portion of the steam is then led to the pilot radiator 16 through the pipe 18 in which is inserted the adjustable valve 19. The condensate from this pilot radiator flows through pipes 20 and 21 to a thermostat of conventional design, and escapes through pipe 29 and the trap 30 to the return line 31. The thermostat is of the expanding fluid type, and is so arranged that the expansion and contractions of the fluid closes and opens the control valve 15 which is of the "all on or all off" type (see Fig. 2). Ordinarily the temperature of the condensate from the pilot radiator 16 is insufficient to close the control valve 15. Steam at constant pressure therefore flows through pipe 4 to the conventional system of radiators and a little is bled off through pipe 27 to the compensating device which, in this figure, is made up of the valve 28 and the radiator 17. When this steam reaches pipe 20 it flows through a check valve (not shown) into pipe 21, and from there to the jacket of the thermostat 22 along with the condensate from the pilot radiator 16. This steam reheats the condensate and thermostat; the fluid in the thermostat becomes greatly expanded and closes the control valve 15, thus shutting off steam from the conventional system of radiators.

The temperature of the thermostat then tends to fall to the temperature of the condensate from the pilot radiator. The time required for the temperature to fall sufficiently to open the control valve 15 will depend upon the rate of condensation in the pilot radiator 16. But this rate of condensation will depend upon the temperature of the air surrounding the pilot radiator. In this way the time interval between successive impulses of steam into the conventional system of radiators depends upon the temperature of the air in contact with the pilot radiator. Obviously there may be several pilot radiators connected in parallel as shown by the radiators 16 and 36 in Figure 1, and 16' and 17' in Figure 3, or there may be several pilot radiators connected in series, and these may be situated in any suitable locations in the space whose temperatures is to be regulated. For instance they may be at opposite ends of the same hallway, or on separate floors. A very small one may even be placed outdoors in order to help compensate for large changes in outdoor temperature.

Obviously, the pilot radiator could be omitted without seriously impairing the constancy of temperature of the heated room or rooms, if only the outdoor temperature remains nearly constant. In such a case I retain the efficiency of condensing to a pressure lower than that of the return line, but I lose the property of maintaining a constant temperature when the outdoor temperature changes.

In the embodiment of the invention as illustrated in Figure 3, I employ a multiple point control or, that is to say, the action of the valve 15' is under control of any one of a number of pilot radiators. In this embodiment the pilot radiators 16' and 17' are arranged upon different floors although it is to be understood that they can be otherwise arranged in spaced or separated relation as conditions may demand.

Each of these radiators 16' and 17' operates to produce the same results as obtained by the pilot radiator 16 and the compensating radiator 17 referred to in the first embodiment of my invention. The radiators 16' and 17' are coupled in parallel with the risers 38 and 39 leading from the main distributing line 4' with the valve 15' interposed.

in the line 4' at a point between the points of communication of the risers 38 and 39 with said line. The riser 38 has interposed therein the main limiting valve 40 and the riser 39 has interposed 5 therein the secondary limiting valve 41, the valve 40 being the equivalent of the valve 19 shown in the first form of my invention while the valve 41 is the equivalent of the valve 28 shown in this former arrangement.

- 10 In communication with both of the radiators 16' and 17' is a vertically disposed pipe line 42 which discharges at its lower end within the casing or shell 43. This casing or shell 43 provides a pocket for the thermostatic element 23' coating with the 15 valve 15' in the same manner and for the same purpose as hereinbefore set forth with respect to the thermostatic element 23 and valve 15 comprised in the first embodiment of my invention. The distributing line 4' also has interposed there- 20 in a reducer valve 9' to assure even pressure of steam entering the pilot radiators 16' and 17'.

The variations in the temperature of the condensate delivered within the casing or shell 43 from either or both of the pilot radiators 16' and 25 17' will result in the requisite functioning of the thermostat 23' to obtain the desired operation of the valve 15' after the manner hereinbefore described and illustrated in connection with the first embodiment of the invention. With the valve 30 15' open steam will pass through the line 39 and beyond the properly set valve 41 into either of the two radiators 16' and 17' and pass there- 35 through and into the casing or shell 43 to reheat the condensate therein for the same purpose as hereinbefore explained with respect to the compensating radiator 17.

It is to be stated at this time that the riser 39 can be dispensed with although when this line is omitted it is to be understood that the closing of 40 the valve 15' will be dependent wholly upon the temperature of the air surrounding either or both of the pilot radiators 16' and 17'. With the temperature of the air surrounding the pilot radiators 16' and 17' above the predetermined air temperature 45 the condensate within the casing or shell 43 will be of a temperature to cause the thermostat 23' to function to close the valve 15' and maintain the same closed. As this air temperature drops below the predetermined air temperature, 50 the condensate will of course fall to the temperature causing the thermostat 23' to function in a manner to open the valve 15'.

In the embodiment of my invention as illustrated in Figure 4, the pilot radiator 16^a has its 55 opposite end portions connected by the risers 38' and 39' with the distributor pipe line 4^a, and interposed in the riser 38' is the main limiting valve 44 and in the riser 39' is a secondary limiting valve 45. The automatically operated valve 15^a is inter- 60 posed in the main distributor line 4^a between the points of communication of the risers 38' and 39'. The riser 38' has interposed therein a reducer valve 46 to maintain even pressure of steam entering the pilot radiator 16^a through the riser 65 38'. Extending within the pilot radiator 16^a is a thermostatic element 23^a operatively connected, as at 25^a, with the valve 15^a, the opening and closing of the valve 15^a being dependent upon the rise and fall of the temperature of the condensate within the radiator 16^a with respect to the temperature necessary to cause the thermo- 70 stat 23^a to function to close the valve 15^a.

When the valve 15^a is opened steam enters the 75 system proper and also enters the pilot radiator 16^a through the riser 39' to reheat the thermostat

23^a for the same purposes as hereinbefore explained with respect to the compensating radiator 17.

While hereinbefore describing the various embodiments of my invention I have particularly 5 specified the location of reducer valves, it is to be stated that additional valves of this character may be employed where deemed desirable.

While it is to be noted that the flow through each of the lines 27, 39 and 39' is limited, yet 10 such flow is not fixed but is variable depending upon the opening of the valve 15, 15' or 15^a. It is also to be particularly noted that the embodiment of my invention as illustrated in Figure 4 it is not the exhaust steam from a radiator that 15 actuates the device but steam bled from the steam supply to the radiators that effects the thermo- stat to actuate the device.

The self-created partial vacuum periods occurring between impulses are of particular importance in view of the fact that economical operation of the system is assured since the higher vacuum thus obtained permits the transmission of a greater portion of the heat units in the steam to the air surrounding the radiators than can be obtained with the radiators under pressure. These vacuum periods are sustained by a check valve in the return line leading from the regular radiators until the next impulse occurs. 20 25

It is believed to be apparent from the foregoing that the control of the flow of the steam is intermittent and gauged by the resultant of the previous impulse thereby establishing an impulse method of flow of the steam. This is of decided advantage over the constant admission of steam 30 to a heating system as it is possible to circulate steam through a system under high vacuum. In other words, my improved system establishes a governed impulse method of flow or may be further defined as a regulated impulse method of 35 flow of the steam.

By use of the pilot radiator as embodied in the several embodiments of my invention as herein disclosed it is believed to be clearly understood that such radiator extends within the area of heat 45 loss or the coldest strata of atmosphere within the building area.

From the foregoing description it is thought to be obvious that steam heating system constructed in accordance with my invention is particularly 50 well adapted for use by reason of the convenience and facility with which it may be assembled and operated, and it will also be obvious that my invention is susceptible of some change and modification without departing from the principles and 55 spirit thereof and for this reason I do not wish to be understood as limiting myself to the precise arrangement and formation of the several parts herein shown in carrying out my invention in 60 practice except as hereinafter claimed.

I claim:—

1. A steam heating system which consists of a combination of a plurality of radiators and a device actuated by the temperature of the exhaust 65 steam from one of the plurality of radiators for giving the system an intermittent supply of steam.

2. A steam heating system which consists of a combination of a plurality of radiators and a device governed by the temperature of the condensate from a pilot radiator for giving the radiators an intermittent supply of steam. 70

3. A steam heating system which consists of a combination of a plurality of radiators and a device for giving these radiators an intermittent 75

- supply of steam; said device being governed by the temperature of the condensate from a pilot radiator fed with steam from a substantially constant pressure source.
5. A steam heating system which consists of a combination of a plurality of radiators and a device for giving these radiators an intermittent supply of steam; said device being governed by the temperature of the condensate from a pilot radiator fed with steam whose pressure is substantially constant.
10. A steam heating system which consists of a combination of a plurality of radiators and a device for giving these radiators an intermittent supply of steam; said device being governed by the temperature of the condensate from a pilot radiator fed with steam whose pressure is substantially constant, and by the temperature of the exhaust steam from a second condensing device fed from the steam pipes which feed one of the plurality of radiators.
15. A steam heating system which consists of a combination of a plurality of radiators and a thermostatic device capable of turning the steam on and off from said radiators; said device being governed by the temperature of the condensate from a pilot radiator which is fed with steam the pressure of which is substantially constant, and by the temperature of the exhaust steam from a second condensing device which is fed from the same steam pipes which feed one of the plurality of radiators.
20. A steam heating system which consists of a combination of a plurality of radiators and a thermostatic device for controlling the supply of steam to the radiators, the said thermostatic device being directly influenced by the temperature of steam bled from the steam supply to the radiators.
25. A steam heating system which consists of a combination of a plurality of radiators and a thermostatic device for controlling the supply of steam to the radiators, the said thermostatic device being directly influenced by the temperature of the air in the area being heated being directly effected by the temperature of steam from the same pipe which feeds the radiators.
30. A steam heating system which consists of a combination of a plurality of radiators and a means for turning the steam off and on for the same; said means consisting of:
- (a) a means for condensing steam from a substantially constant pressure source,
- (b) a means for bleeding steam from the intermittent supply of the above mentioned radiators, into a second condensing device,
- (c) a thermostat connected to a valve which is capable of turning the steam on and shutting it off from the conventional radiators; the valve being turned on when the temperature falls below a predetermined value determined by the condensate from (a), and being turned off when the temperature exceeds a predetermined value determined by the exhaust steam from (b).
35. In a steam heating system, a plurality of radiators, one of which constitutes a pilot radiator, a steam line for the radiators, a valve for opening and closing the flow through the steam line to all the radiators except the pilot radiator, and a thermostat operating upon the variation in temperatures of the condensate from the pilot radiator to open or close the valve.
40. In a steam heating system including a steam line, a valve in said line and a thermostat for operating the valve, a pilot radiator, means for supplying said pilot radiator with a fixed limited amount of steam, said steam condensing as a result of the temperature of the air contacting with the pilot radiator, the temperature of the condensate varying with the temperature of said air, and means for delivering the condensate to the thermostat, the variations in the temperature of the condensate causing the thermostat to operate to open or close the valve.
45. A steam heating system which consists of a combination of a plurality of radiators and a device actuated by the temperature of steam bled from the steam supply to the radiators for giving these radiators an intermittent supply of steam.
50. A steam heating system which consists of a combination of a plurality of radiators and a device governed by the temperature of the condensate from a pilot radiator and by the temperature of steam bled from the steam supply to the radiators for giving these radiators an intermittent supply of steam.
55. A steam heating system which consists of a combination of a plurality of radiators and a device for giving these radiators an intermittent supply of steam, said device being governed by the temperature of the condensate from a pilot radiator fed with steam from an irregular pressure source whose average pressure is substantially constant.
60. A steam heating system consisting of a combination of a plurality of radiators and a device for giving these radiators an intermittent supply of steam, said device being actuated by the temperature of steam bled from the supply to the radiators and governed by the temperature of the condensate from a pilot radiator fed with steam from a substantially constant pressure source.
65. A steam heating system consisting of a combination of a plurality of radiators and a thermostatic device for controlling the supply of steam to the radiators, the said thermostatic device used to control the temperature of the air in the area being heated being directly effected by the temperature of steam from the same pipe which feeds the radiators.
70. A steam heating system consisting of a combination of a plurality of radiators, a supply valve operated by the action of a thermostat, means for effecting the thermostat from the changes of the temperature of the condensate from a pilot radiator, and means for effecting the thermostat by reheating such condensate.
75. A steam heating system which consists of a combination of a plurality of radiators and a device for giving these radiators an intermittent supply of steam; said device being governed by the temperature of the condensate from a pilot radiator fed with steam whose pressure is substantially constant and by the temperature of the exhaust steam from a condensing device fed from the steam pipes which feed the radiators.
80. A steam heating system which consists of a combination of a plurality of radiators and a thermostatic device capable of turning the steam on and off from said radiators; said device being governed by the temperature of the condensate from a pilot radiator which is fed with steam the pressure of which is substantially constant and by the temperature of the exhaust steam from a second device which is fed from the same steam pipes which feed the radiators.

GROVE STARR.
